US00D782976S

(12) **United States Design Patent** (10) **Patent No.:** **US D782,976 S**
(45) **Date of Patent:** **** Apr. 4, 2017**

(54) **WIRELESS CHARGING TRANSMITTER**

(71) Applicant: **Shenzhen Qianhai headfree Tech Co., Ltd**, Shenzhen (CN)

(72) Inventor: **Ming Zhang**, Shenzhen (CN)

(73) Assignee: **Shenzhen Qianhai headfree Tech Co., Ltd**, Shenzhen (CN)

(**) Term: **15 Years**

(21) Appl. No.: **29/553,171**

(22) Filed: **Jan. 29, 2016**

(51) **LOC (10) Cl.** **13-02**

(52) **U.S. Cl.**

USPC **D13/108**

(57) **CLAIM**

The ornamental design for a wireless charging transmitter, as shown and described.

DESCRIPTION

FIG. 1 is a front view of a wireless charging transmitter; FIG. 2 is a back view of the wireless charging transmitter; FIG. 3 is a left side view of the wireless charging transmitter; FIG. 4 is a right side view of the wireless charging transmitter;

FIG. 5 is a top plan view of the wireless charging transmitter;

FIG. 6 is a bottom plan view of the wireless charging transmitter;

FIG. 7 is a front perspective view of the wireless charging transmitter; and,

FIG. 8 is a back perspective view of the wireless charging transmitter.
